UNITED STATES PATENT OFFICE.

JOHN P. MCCOY, OF PHILADELPHIA, PENNSYLVANIA.

SHAKING MACHINE.

1,409,052.

Specification of Letters Patent.

Patented Mar. 7, 1922.

Application filed September 9, 1920. Serial No. 409,051.

To all whom it may concern:

Be it known that I, JOHN P. MCCOY, a citizen of the United States, residing in Philadelphia, Pennsylvania, have invented 5 Shaking Machines, of which the following is a specification.

This invention relates to mechanism for violently agitating a container, usually in the form of an open work- or perforated 10 basket, for the purpose of separating or removing a portion of the contents thereof from the remainder; one object of said invention being to provide a device of this character which shall be especially adapted 15 for removing the surplus solid or semi-liquid metal from articles after these have been dipped in a galvanizing bath or other mass of molten metal.

A further object of the invention is to 20 provide a relatively simple, compact and substantial machine for rapidly reciprocating a basket, together with novel means for supporting said basket so that it may be readily placed on or removed from the machine.

These objects and other advantageous 25 ends I attain as hereinafter set forth, reference being had to the accompanying drawings, in which,

30 Figs. 1 and 2 are respectively a side and a front elevation of a shaking machine constructed in accordance with my invention; and

35 Fig. 3 is a horizontal section on the line 3—3, Fig. 2.

In the above drawings 1 represents a vertical frame member in the form of an I-beam and 2 a portion of a horizontal top frame member, having one end connected 40 to said vertical member. The machine illustrated includes and is mounted on one end of the top frame member 2 and on the single vertical member 1 illustrated, there being in the present case a similar machine 45 mounted on the other end of the member 2 and on a second vertical frame member. Since however this second machine with its supporting structure is identical with that illustrated, it has not been shown.

50 The top frame member 2 which is preferably in the form of a rolled channel section, carries bearings 3 in which is mounted a shaft 4 carrying fast and loose pulleys 5 and 6. Said shaft projects over the vertical frame member 1 and has keyed or otherwise fixed to its outer end an eccentric 7

having a strap 8 to which is connected a vertically extending rod 9. The vertical frame member 1 has mounted on both sides of its web a pair of vertically extending reinforcing plates 10 and 11 which with it have formed in them a vertically extending guide slot 12, serving as a guideway for a cross head 13 to which a head 14 on the eccentric rod 9 is operatively connected by 65 a pin 15. This pin extends through said cross head, which is formed to fit the guide slot 12 in the plates 10 and 11, and has mounted on its extremity a nut 16 whereby a slide 17 is held against said plate 10. 70

Bolted or otherwise rigidly fixed to the cross head 13 is a yoke piece 18 having parallel, substantially horizontal arms whose adjacent faces each have projecting from them a pair of upper pins 19 and a lower 75 pin 20. The pins of each of the yoke arms are designed to receive and removably hold one of the two parallel U-shaped handles 21 of an open mesh or perforated metal basket 22, and the construction and arrangement is such that said handles may be 80 slightly bent toward each other to permit of the upper end of each of them being sprung or forced over the pin 20 and under the two pins 19 on one of the arms. 85

A pair of guide plates 23 mounted on the bearings 3 are formed with openings for the reception of a longitudinally movable belt shifter bar 24 carrying a belt engaging member 25 and having an operating handle 90 26 whereby it may be moved to shift a power driven belt 27 from the loose pulley 6 to the fast pulley 5 or vice versa.

With the above described arrangement of parts any material to be sifted, mixed or 95 agitated is placed in the basket 22, which in the present instance is especially designed for the treatment of metal articles immediately after they have been dipped in galvanizing or tinning metal. The basket 100 shown, after being dipped with its contents into the molten metal, has its handles respectively engaged with the pins 19 and 20 of the two arms at the yoke 18, so that it is suspended therefrom. By means of the handle 105 26 and rod 24, the belt 27 is shifted from the loose to the tight pulley 5, so that the shaft 4 is turned and through the eccentric 7, the rod 9 and the cross head 13 are rapidly reciprocated in a vertical line.

As a consequence the basket with its contents is violently agitated and the surplus

semi-molten or solid metal adhering to or mixed with the articles in the basket is dislodged and caused to pass through the openings in said basket, so that the tinned or galvanized articles are cleaned and effectually separated from such surplus material. After having been operated for a time necessary to attain the above noted desired result the belt 27 is shifted to the loose pulley and the basket with its contents removed by springing the handles 21 toward each other to cause their upper ends to clear the pins 19 and 20.

From the above description it will be noted that the machine is not only simple and substantial in construction, but its parts are so arranged that it will permit the necessary agitation of the basket 22 and its contents to effectively remove surplus metal from galvanized or tinned articles and may also be conveniently utilized for sifting, mixing or separating articles or substances of different sizes;—it being understood that the shaft 4 is turned at a speed which will

give the basket necessary agitation required to accomplish the desired end.

I claim:

1. The combination of a supporting structure having a vertical guideway therein; a cross head movable in the guideway; means for reciprocating said cross head; a yoke connected to the cross head and including two substantially parallel arms; projections on each of said yoke arms; and a basket having handles formed to removably engage the projections of said yoke arms respectively.

2. The combination of a vertically reciprocable cross head; a guide therefor; means for reciprocating the cross head in the guide; a yoke carried by the cross head and including two substantially parallel arms; three pins carried by each of said arms and arranged one between and below the other two; with a basket having substantially U-shaped handles formed to removably fit over the lower pin and under the two upper pins of the yoke arms respectively.

JOHN P. McCOY.
